UNITED STATES PATENT OFFICE.

WILLIAM L. BARRON, OF NEWARK, NEW JERSEY, ASSIGNOR TO THE SINGER MANUFACTURING COMPANY, A CORPORATION OF NEW JERSEY.

WORK-HOLDER FOR SEWING-MACHINES.

1,366,348.

Specification of Letters Patent. Patented Jan. 25, 1921.

Application filed July 13, 1918. Serial No. 244,695.

To all whom it may concern:

Be it known that I, WILLIAM L. BARRON, a citizen of the United States, residing at Newark, in the county of Essex and State of New Jersey, have invented certain new and useful Improvements in Work-Holders for Sewing-Machines, of which the following is a specification, reference being had therein to the accompanying drawings.

10 This invention relates to work-holders for button sewing machines and has for an object to improve the work-holder disclosed in my application Serial No. 161,404, filed April 12, 1917 so that it will successfully 15 handle, not only buttons of the smaller and medium sizes, but also buttons of the largest sizes such as are used on heavy overcoats and the like.

In attempting to make use of my prior 20 work-holder in sewing on very large buttons, it is found that there is a tendency for the button to be lifted out of engagement with the clamping jaws, due to the reactionary upward pressure of the body-fabric upon 25 the central portion of the curved lower face of the button. With certain other well known forms of work-holders including co-acting button-gripping jaws which are spring-pressed toward the fabric, it is necessary 30 to elevate said jaws to relieve them of the reactionary upward pressure of the fabric before they will readily yield to the insertion of a button. To overcome the ill effects of this reactionary upward pressure 35 of the fabric upon the button, I now interpose presser means between the button-gripping elements and the work-supporting plate; said presser means being designed to hold the body-fabric against the work-support 40 and relieve the button and button-gripping elements of the objectionable reactionary upward pressure referred to.

The presser means may comprise a foot-plate having a substantially rigid upwardly 45 extending shank fixedly secured to the forward end of the usual supporting bar for the button-gripping levers. The foot-plate is preferably circular in form and is provided with a centrally disposed aperture to receive the stitches; said aperture opening to the forward edge of the foot-plate to permit removal of the stitched work.

In the accompanying drawings, Figure 1 is a perspective view of the work-holder em-

bodying the present invention. Fig. 2 is a 55 front end elevation of the same. Fig. 3 is a bottom plan view of the upper or button-holding element of the work-holder and Fig. 4 is a perspective view of the presser device which is interposed between the upper and 60 lower elements of the work-holder in accordance with the present improvement.

For the purposes of this disclosure the invention may be described as embodied in a work-holder of the well known type disclosed in the United States patent to J. J. Sullivan, No. 777,564 and comprising a slide-bar 1 carrying a work-supporting plate 2 at its forward end. Mounted upon the slide-bar 1 near its rearward end is a block 3 in 70 which is loosely mounted the forwardly projecting button-clamp supporting bar 4 which is pressed toward the slide-bar 1 by means of the usual leaf-spring 5. Pivotally mounted at 6', 6' upon the supporting bar 75 4 are the clamping levers 6, 6 formed at their in-turned extremities with opposed clamping jaws each of which comprises a button-edge engaging shoulder 7 and a button-face supporting ledge 8. Projecting 80 downwardly from the levers 6, 6 are pins 9, 9 which enter the rearwardly converging slots 10, 10 formed in the slide-plate 11 secured to the usual slide-bar 12 sustained beneath the supporting arm 4 and carrying the 85 stud-screw 13 which projects upwardly through a slot 14 in said supporting bar and is connected by the spring 15 to the clamp-lifting post 16.

Superimposed upon the levers 6, 6 are 90 flat springs 17, 17 each of which follows the contour of its respective lever and at its rearward end is secured to the latter by a screw 18 and steady-pin 19. The free end of each of the springs 17, 17 is bent downwardly and horizontally to form a presser-finger 20 the button-engaging surface of which is normally spaced above the button-face supporting ledge 8 of its respective lever a distance less than the height or thickness 100 of the adjacent button-edge gripping shoulder 7.

The front ends 21, 21 of the horizontal or button-engaging portions of the presser-fingers 20, 20 are extended forwardly and 105 upwardly to facilitate insertion of blunt edged buttons into the spaces between the fingers 20, 20 and ledges 8, 8. The ledges

8, 8 are extended forwardly in advance of the front ends 21, 21 of the presser-fingers in order that the edge of a button may be rested upon the ledges 8, 8 before it is pushed under the presser-fingers 20, 20.

The supporting bar 4 carries an adjustable stop 22 to limit the approach of the levers 6, 6 under the influence of the spring 15 and plate 11. Said stop 22 is preferably 10 in the form of a lever pivoted at one end to the bar 4 by a screw 23 and formed at its opposite end with a finger-piece 24 and slotted segmental portion 25 through which passes a clamping-screw 26. When the stop-lever 22 is set to space the button-edge clamping shoulders 7, 7 a given distance apart, buttons whose diameters are but slightly greater than said given distance may 15 be readily forced between said shoulders and into engagement with the usual button-centering stop 27 carried by the slide-bar 12.

When a button of very large diameter is inserted between the button-gripping shoulders 7, 7, it is found that the central portion 25 of the under face of the button projects somewhat below the plane of the under faces of the button-sustaining ledges so that when the clamped button is lowered upon the fabric the reactionary upward pressure of the latter tends to lift the button out of gripping relation with the button-gripping elements.

I overcome this difficulty by interposing presser means between the fabric and the button-gripping elements to relieve the latter and the button of the said reactionary pressure. While the presser means may take various forms I prefer to provide a substantially rigid presser-foot which may conveniently be bent up out of sheet-metal. The foot preferably comprises a horizontally arranged foot-plate 28 of circular form, supported by a vertical shank 29 slotted at 30 for passage of the button stop 27 and secured at its upper extremity to the forward end of the bar 4 by the screws 31. The foot-plate 28 is formed with a central aperture 32 which is opened in front at 33 to permit removal of the stitched work. In the present instance it is not necessary that the button be inserted between the button-clamping jaws before the upper member of the work-clamp is lowered upon the fabric. If desired, the fabric may first be inserted between the work-supporting plate 2 and presser-plate 28 and adjusted so that the position on the fabric where the button is to be attached, is located centrally of the aperture 32 in the presser-plate; the view 60 of said aperture not being obstructed by a superposed button. After the fabric is accurately located and clamped in position, the button-clamping jaws, being free from the upward pressure of the fabric, will readily yield laterally to the insertion of the

button, and will permit the button to be readily turned to position the holes in register with the needle-path.

In the particular embodiment of the invention shown and described, the work-holder is adapted to be shifted laterally of the reciprocating needle 34 which passes through the usual needle-hole 35 in the throat-plate 36 for coöperation with a suitable loop-taker. It is to be understood, however, that insofar as the present invention is concerned, it is immaterial how the relative stitch-positioning movements of the stitch-forming mechanism and work-holder are obtained. Furthermore, it will be apparent from the foregoing to those skilled in the art that various changes may be made in the form and arrangement of the parts without departure from or sacrifice of the advantages of the invention.

Having thus set forth the nature of the invention, what I claim herein is—

1. Work-holding mechanism for article-attaching machines comprising, a fabric-support, a presser for holding the fabric against said support, and article holding jaws sustained in operative position at a level above said presser and out of pressure exerting coöperative relation with said fabric-support.

2. Work-holding mechanism for button-sewing machines comprising, a fabric-support, button-gripping means, means at a level between said fabric-support and button-gripping means for pressing the body-fabric against said fabric-support independently of said button-gripping means.

3. Work-holding mechanism for sewing machines comprising, a fabric-support, co-acting article-gripping devices, a carrier therefor spring-pressed toward said fabric-support, and a rigid presser sustained by said carrier and interposed between said fabric-support and article-gripping devices, whereby to relieve said devices and an article gripped thereby of the reactionary upward pressure of the fabric.

4. Work-holding mechanism for sewing machines comprising, a fabric-support, co-acting article-gripping devices, a carrier therefor spring-pressed toward said fabric-support, and a presser interposed between said fabric-support and said devices and acting independently of said devices to transmit the spring-pressure on said carrier to the fabric, whereby to relieve said devices and an article gripped thereby of the reactionary upward pressure of the fabric.

5. A work-holder for sewing machines comprising, a fabric-supporting plate having a flat fabric supporting surface, coacting button gripping levers terminating in jaws adapted to grip the edge of a flat button, a carrier therefor upon which said levers are pivotally mounted, a spring for

pressing said carrier toward said fabric-supporting plate, and a presser joined to said carrier in advance of the pivots for said levers and acting independently of said 5 levers to transmit the spring-pressure upon said carrier to the fabric.

6. A work-holder for sewing machines comprising, a fabric-supporting plate having a flat fabric supporting surface, coacting 10 button gripping levers terminating in jaws adapted to grip the edge of a flat button, a carrier for said levers upon which they are pivotally mounted, a spring for pressing said carrier toward said fabric-supporting 15 plate, and a presser joined to said carrier in advance of the pivots for said levers and acting independently of said levers to transmit the spring-pressure upon said carrier to the fabric, said presser comprising a sub- 20 stantially flat foot-plate and a vertically extending shank substantially rigid with said foot-plate.

7. A work-holder for flat button sewing machines comprising, a fabric-support hav-

ing a needle aperture and a flat upper surface embracing said needle aperture, a presser for holding the fabric flat upon said fabric-support, and flat button holding jaws sustained in operative position above said presser and out of pressure exerting coöperative relation with the fabric-support. 25

8. Work-holding mechanism for button sewing machines comprising, a fabric support, a presser for holding the fabric against said support, and coacting jaws for holding 30 a button in sewing position out of contact relation with the fabric upon said fabric support. 35

9. Work-holding mechanism for sewing machines comprising, a fabric support, a 40 presser for holding the fabric against said support, and article holding jaws sustained in operative position above said support and out of pressure exerting coöperative relation with the fabric. 45

In testimony whereof I have signed my name to this specification.

WILLIAM L. BARRON.
